UNITED STATES PATENT OFFICE.

HARRY JAFFE, OF CHICAGO, ILLINOIS.

AUTOMOBILE RADIATOR.

Application filed September 15, 1921. Serial No. 500,919.

To all whom it may concern:

Be it known that I, HARRY JAFFE, a citizen of the United States, and resident of Chicago, in the county of Cook and State 5 of Illinois, have invented certain new and useful Improvements in an Automobile Radiator, of which the following is a specification.

My invention relates to improvements in 10 radiators for automobiles and has special reference to radiators of the kind in which the core is made up of strips of thin sheet metal.

An object of my invention is to provide 15 a radiator of the character named which shall be capable of being constructed at relatively low cost; which shall be so constructed that there shall be sufficient interior expansibility allowed so that the radiator 20 cannot be fractured or damaged by freezing, and which shall be of substantially maximum efficiency in the cooling of the water.

A further object of my invention is to 25 provide a radiator core of such form, construction and assembly that it will be a relatively simple matter to remove a damaged part or section thereof and insert a new part within the opening provided by the removal of the damaged part and without 30 the necessity of separating or disassembling the parts of the radiator and even without the necessity of removing the radiator from its installed position on an automobile.

35 A further object of my invention is to provide a radiator core of such construction that a section within the core and extending from front to back can be readily removed in making repairs and a new part or 40 section inserted which fills the opening produced, the new part being capable of being tightly sealed into the core by merely soldering the joints at the front and rear faces only of the radiator.

45 The invention will be more readily understood by reference to the accompanying drawings forming part of this specification and in which,

Fig. 1 is a front view of a radiator constructed in accordance with my invention;

Fig. 2 is an enlarged fragmentary front view of the radiator core;

Fig. 3 is a still more enlarged frag-

mentary vertical cross sectional view of the core on the line 3—3 of Fig. 4;

Fig. 4 is a fragmentary top plan view 55 of the radiator core;

Fig. 5 is a side elevational view of one vertical section of the core as seen on the plane 5—5 of Fig. 2;

Fig. 6 is a similar view as seen on the plane 6—6 of Fig. 2;

Fig. 7 shows a front view of a fragment 60 of a radiator core prepared to receive a repair section;

Fig. 8 is a front view of a repair section;

Fig. 9 is a front view of the fragment of 65 the radiator shown in Fig. 7, as it would appear when repaired, and,

Fig. 10 is a fragmentary horizontal section 70 on the line 10—10 of Fig. 2.

In said drawings, 1 indicates the radiator core which is arranged within a suitable radiator shell having an upper header 2, provided with a filling opening 3, of the 75 usual kind and a lower header 4. The core 1 is arranged between the two headers and is provided with vertical water passages through which the water flows downwardly 80 as it is cooled. The water passages alternate with suitable horizontal air passages, as is usual, through which the air flows horizontally to cool the water within the tubes.

The core 1 comprises a series of vertical 85 water tubes 5. Each water tube 5 is composed of two similar side walls 6, made of sheet metal. The tubes extend vertically from the lower header 4, up to the upper header 2, and are suitably sealed or connected to the headers. Each of the side 90 walls 6 of each tube is folded and crimped between its ends to provide outwardly extending double thickness fins 7, alternating with similar fins 8, which are shorter than the fins 7. Each sheet or side wall 6 is of 95 a width to extend from front to back of the radiator and the front and rear margins of the strips are formed inwardly, as shown at 9, so that the two margins of the two strips forming a single water tube are brought into contact. Then when the core is completed by soldering the water tubes 5 are closed from their lower ends to their upper ends. At the ends of the tubes the sheets 100 are bent outwardly as at 10, forming flanges 105 for contact with and sealing to the upper

and lower headers in the usual manner when completing the radiator.

Between the fins 7 and 8 each sheet is provided with one or more outwardly rounded 5 corrugations 11, which add to the interior capacity of the tube, to render the walls of the tube somewhat yielding and to afford additional heat radiating surface. At the front and rear margins of the tubes the corrugations 11, disappear into the edge flanges 12, forming inclined end shoulders 13, against the forward ones of which the air impinges as it passes through the radiator between the water tubes.

15 Between the water tubes I arrange sheet metal spacers 14, which extend from the bottom to the top of the core and with which the longer fins 7 contact at their adjacent edges. These spacers are permanently 20 joined to the edges of the fins 7 when the core is immersed in melted solder in the process of the manufacture of the core. The upper and lower edges of these spacers may be received between the adjacent edges 25 of the flanges 10, as best shown in Fig. 3, and provide flat upper and lower surfaces or ends for contact with the upper and lower headers.

The formation of the radiator with the 30 water tubes which are provided with alternate longer and shorter fins and the spacer strips, provides substantially square openings 15, extending from front to rear and providing a cellular appearance to the radiator which is particularly attractive.

To present a uniform appearance within the openings 15, I preferably cut openings 16 in the forward edges of the spacer strips 14, the openings having a vertical width 40 substantially equal to the transverse space between opposed edges of the shorter fins 8, providing, as best shown in Figs. 7, 8 and 9, a radiator of uniform lines and openings.

It will be understood that the spacer 45 strips 14 are continuous at their rear edges 17 from top to bottom of the radiator and between the openings 16 provided in their forward edges, and which openings 16 may obviously extend from the front face suitable distances toward the rear. The tongues 50 18, of the spacer strips extend clear to the front face of the radiator between the longer fins 7.

In forming the walls 6 of the water tubes 55 5, in the production of the fins 7 and 8, I preferably so form the fins that their upper and lower walls are in close contact with each other, as best shown in Fig. 3, although such formation of the fins is not absolutely 60 essential to the other important features of the core.

The water tubes 5, being continuous from the top to the bottom of the core and being substantially straight water passages, the 65 core lends itself effectively to the feature of

completely coating the inside and the outside of all of the parts of the core with solder and thus protecting the sheet metal of which the core is made from deterioration by corrosion or otherwise.

In making a core of the form described, I preferably first assemble the requisite number of walls 6 in proper associated arrangement to form the necessary number of water tubes to fill the space in the radiator frame 70 75 preferably stopping the core at the side edges at the center plane of a tube at each side. I assemble the several walls 6 with the necessary number of alternate intermediate spacers 14 and then I tightly clamp the several parts together to hold them properly in assembled relation while completing the core by the soldering operation.

In soldering a core of the kind described I first immerse it in a suitable acid bath to 80 cleanse the surface setting the core upright to permit the liquid to properly drain from the tubes 5, and then completely immerse the core in a bath of melted solder in such manner that the solder flows within all the tubes 85 90 95 5 and completely covers all exterior and interior surfaces. When the core has become thoroughly heated and the solder has coated all interior and exterior surfaces I lift the core from the solder and set it upright again to permit the solder within the tubes 5 to properly drain out and leave the tubes open from top to bottom. I further place the core horizontally to permit all superfluous solder to drain out of the horizontal air passages.

Destruction of radiators by freezing of the water within the tubes results from the impossibility of the parts of the radiator yielding, in the slight degree which is necessary to accommodate the slightly increased volume of the contents when the water is 100 105 changed to ice.

My improved core is so constructed that should it occur that the water within the tubes 5 is frozen, the portions of the walls 6 110 115 which extend between the longer fins 7, can readily yield outwardly on account of the shorter fins 8 not contacting with any wall and this slight yieldability of these portions of the wall I find is sufficient to provide the necessary additional space required to accommodate the ice and without any destructive effect upon the core.

Furthermore, the corrugations 11, which extend substantially the full horizontal 120 125 width from front to back, of the water passages, provides additional yieldability for this purpose.

It frequently occurs in the use of radiators that a portion thereof is damaged by reason of the radiator being forced against some projection or article which presses into the face of the radiator causing the water tubes to leak and necessitating more or less 125 extensive repairs.

As the water tubes in my radiator are completely individually sealed from top to bottom, the side walls thereof being continuous from top to bottom, I can readily remove 5 a damaged portion of the radiator, as best illustrated in Fig. 7. If a portion of the radiator is damaged which would cause one or more water tubes to leak, I preferably proceed as follows:

- 10 I remove a section of the radiator, as shown at 19, where the opening is shown as extending through from front to back of the radiator. The vertical dimension of the opening 19 is defined at its upper side by the 15 upper halves 20, of a horizontal row of the longer fins 7, and likewise the lower wall of the opening as defined by the lower walls 21, of a horizontal row of the longer fins 7. The sides of the opening 19 are defined by the 20 outer walls 22, of one of the water tubes 5, at each side.

It will now be clear that as shown in Fig. 7, I have cut off the two middle water tubes 5, between the upper and lower walls of the 25 opening and I have split the two water tubes 5, at the sides of the opening 19.

For completing the repair I provide a small section 23 of the core, of the same construction as the main body of the core and 30 of dimensions to fit within the opening 19. For instance, in the section 23, shown in Fig. 8, there are two water tubes 5 intermediate between the sides of the section. At each side of the section a half tube 24, is provided 35 and at the top and bottom of the section continuous horizontal walls 25 are provided which are identical with the parts of the fins 7 removed at the top and bottom of the opening 19, and consequently this section 23 fits 40 accurately within the opening 19.

I force the section 23 into the opening 19 until the forward and rear faces of the section correspond or lie in the forward and rear faces of the core and then I solder the 45 joints 26 at the front and rear faces of the core which appear between the peripheries of the ends of the section 23 and the two faces of the core. Having completely soldered these two joints 26, the repair is 50 complete for the reason that no water can escape from any of the water passages which have been cut or opened as each passage in itself is complete and the opening into the core has been completely sealed. 55 Furthermore, each water passage which has been cut is now complete from top to bottom and consequently provides its quota of circulating cross section.

While it is true that at the top and bottom 60 of the sections the intermediate surfaces between the repair section 23 and the core are not completely joined, this is not detrimental for the reason that even if water should seep through between these surfaces, 65 it could not escape from the radiator.

Another feature of my invention resides in the facility with which a small leak or damage could be repaired even on the road by the insertion into the cells of the radiator of a mastic substance such as partly cured 70 rubber, which most car owners now carry with them for repairing tires, or even with a small quantity of chewing gum, such repair being sufficient to stop any slight leak until it can be more thoroughly repaired by 75 the removal of the damaged portion and the insertion of a new section, as has been described.

As many modifications of my invention will readily suggest themselves to one 80 skilled in the art, I do not limit my invention to the particular sequence of steps or to the specific details of construction herein described and claimed.

I claim:

1. A radiator for automobiles comprising top and bottom headers, a core arranged between and sealed to the headers, the core comprising vertically extending transverse thin water tubes made of sheet metal strips, 90 the strips crimped between their ends to provide outwardly extending horizontal double thickness fins, alternate fins being longer than the others, sheet metal spacing strips arranged between the longer 95 strips, the shorter fins projecting freely and the whole joined into a unit by soldering inside and out.

2. In a radiator of the kind described, a pair of water tubes, each tube made of two 100 strips of sheet metal formed for contact at their vertical edge portions, these strips provided with integral outwardly projecting transverse fins uniformly spaced from top to bottom, the alternate fins being shorter 105 than the others, a metal spacer strip arranged between the two tubes and contacting with the longer fins, and the several parts adapted to be permanently joined by soldering.

3. In a radiator of the kind described, a plurality of vertically extending water tubes, each tube comprising side walls of sheet metal, the side walls formed to contact at their forward and rear edge portions, the 115 side walls also formed to present horizontal outwardly extending transverse fins, alternate fins being wider than the others, spacer strips arranged between the water tubes extending from front to back and 120 top to bottom and contacting with the free edges of wide fins and the whole unified by immersion in melted solder.

4. A sheet metal tube for a radiator comprising two sheet metal strips extending 125 longitudinally of the tube, the strips formed for contact at their longitudinal edges and spaced apart between their edges, each strip folded upon itself to form outwardly projecting transverse fins of two widths, one 130

- of the narrower fins arranged between each two of the wider fins, and the said strips being transversely corrugated between the fins, as and for the purpose specified.
5. 5. In a radiator of the kind described, a plurality of thin vertical water tubes, each tube having outwardly projecting transverse integral fins on each side, the fins being of two widths and the narrower fins arranged between the wider fins, a flat spacer strip arranged between adjacent water tubes, and bound between the longer fins, the longer fins of the several tubes arranged in horizontal alinement, the spacer strips 10 ranged between the wider fins, a flat spacer strip arranged between adjacent water tubes, and bound between the longer fins, the longer fins of the several tubes arranged in horizontal alinement, the spacer strips 15 cut away at their forward edges between the shorter fins so that the forward edges of the spacers present the same appearance as the fins.
6. In a radiator of the kind described, a plurality of thin vertical water tubes, each tube having outwardly projecting transverse integral fins on each side, the fins being of two widths and the narrower fins arranged between the wider fins, a flat spacer strip arranged between adjacent water tubes 20 and bound between the wider fins, the wider fins of the several tubes arranged in horizontal alinement, the spacer strips provided at their forward edges with dove-tail shaped openings between the shorter fins of a size so that said forward edges present the same appearance as the fins.

Signed at Chicago, Ill., this 10th day of Sept. 1921.

HARRY JAFFE.
